FIG. 1

FIG. 2

FIG. 3

FIG. 4

FIG. 5

FIG. 6

FIG. 7

FIG. 8

Fig. 1 is a front elevational view of a combined nebulizer and medicine dropper showing my new design, the rear not shown being substantially the same as the front shown;

Fig. 2 is a right side elevational view thereof;

Fig. 3 is a left side elevational view thereof; and

Fig. 4 is a top plan view thereof, the bottom being substantially plain.

Fig. 5 is a front elevational view of a modified form thereof, the rear not shown being substantially the same as the front shown;

Fig. 6 is a right side elevational view of the modified form thereof;

Fig. 7 is a left side elevational view of the modified form thereof; and

Fig. 8 is a top plan view of the modified form thereof, the bottom being substantially plain.

This application is a continuation of my copending design applications D. 56,224 and D. 56,225 (filed June 5, 1959, and now abandoned).

I claim:

The ornamental design for a combined nebulizer and medicine dropper, as shown and described.
